UNITED STATES PATENT OFFICE.

HERBERT E. WHITE, OF YOUNGSTOWN, OHIO, ASSIGNOR TO THE TRUSCON STEEL COMPANY, OF YOUNGSTOWN, OHIO, A CORPORATION OF MICHIGAN.

METAL-EXPANDING MACHINE.

1,417,706.

Specification of Letters Patent. Patented May 30, 1922.

Application filed December 11, 1920. Serial No. 430,031.

To all whom it may concern:

Be it known that I, HERBERT E. WHITE, citizen of the United States, residing at Youngstown, in the county of Mahoning and 5 State of Ohio, have invented certain new and useful Improvements in Metal-Expanding Machines, of which the following is a specification.

This invention relates to metal expanding 10 machines, particularly of the type wherein the opposite edges of a slotted sheet metal blank are guided along diverging paths, causing a lateral spreading of the blank, in fan-like formation, thereby opening the slits 15 into meshes.

In machines of the type referred to, it has been found practically impossible to grasp the sheet tightly enough, between the feeding members or rollers, to prevent the same 20 slipping out laterally or sidewise, thus making the operation of expanding a slotted metal sheet, in such type of machine, unreliable and expensive.

Accordingly, the purpose of the present 25 invention is to provide a novel association of instrumentalities, in combination with divergently related expanding means, operating to expeditiously and accurately handle a previously slotted metal sheet to uniformly 30 expand the same, without possibility of sidewise or lateral displacement of the sheet during the expanding action. To that end, the invention contemplates an improvement which utilizes the physical formation of the 35 sheet as a part of the means to definitely and positively interlock it with the feeding members and guides, whereby the sheet will be held to a fixed path of movement, and absolutely prevented from slipping out of position 40 at any stage of the operation. This permits the machine to be operated at a maximum speed without danger of the sheet moving out of its proper path or without danger of a defective expanding action.

With the above and other objects in view which will more readily appear as the nature of the invention is better understood, the same consists in the novel construction, combination and arrangement of parts herein- 50 after more fully described, illustrated and claimed.

A preferred and practical embodiment of the invention is shown in the accompanying drawings, in which:—

Figure 1 is a side elevation of a machine 55 embodying the present improvements.

Figure 2 is a top plan view thereof.

Figure 3 is a vertical sectional view of the machine showing the upper jaw of the expanding means.

Figure 4 is an enlarged detail sectional view taken transversely of the upper and lower jaws, and illustrating the manner in which the slotted blank interlocks with the feeding means.

Figure 5 is a top plan view of one of the expander jaws showing the stationary dies and rotatable feeding rollers.

Figure 6 is a vertical cross sectional view taken on the line 6—6 of Figure 5. 70

Figure 7 is a more or less diagrammatic view illustrating the manner of engagement between the feed rolls and the blank in opening the slits into meshes.

Figure 8 is a diagrammatic view of the 75 upper and lower jaws, showing the relative relation thereof to the superposed rolls of the blank feeding unit.

Figure 9 is a plan view of the form of slotted blank upon which the machine operates.

Figure 10 is a diagrammatic cross sectional view of the blank shown in Figure 4, showing the raised and depressed strands, producing the grooves which interlock with 85 the feeding instrumentalities as clearly shown in Figure 4.

Similar reference numerals designate similar parts throughout the several figures of the drawings.

As previously indicated, the improvements, constituting the present invention, possess special utility in their application to a type of machine employing divergently related expanding members which provide for a 95 fan-like opening of the slotted blank as it is pushed through the machine by the feeding instrumentalities. The slotted blank is of a grooved or channeled formation and the grooves thereof register and interlock with 100 the feeding and guiding elements carried by the said expanding members. Therefore, in

carrying forward the invention a distinguishing feature thereof is in utilizing a grooved or channeled slitted sheet in combination with feeding and guiding means having a direct interlocking engagement therewith, and by reference to the diagrams of Figures 9 and 10 of the drawings the structural characteristics of the said slitted sheet may best be seen. From these views it will be observed that the improvements of the present invention operate in connection with the slitted blank, designated generally by the letter A, in which the strands upon opposite sides of each slit are alternately raised and depressed resulting in the formation of longitudinally extending grooves or channels. In the drawings these longitudinally extending grooves or channels are designated by the reference letter *a* lying between the rows of raised strands *b* at one side of the sheet and between the rows of depressed strands *c* at the opposite side of the sheet. Thus, the slitted blank presents grooves in both faces thereof thereby adapting the sheet mechanically to cooperate with the feeding and guiding units of the present machine in the manner to be hereinafter more fully set forth.

Referring particularly to the structural features of the machine, equipped with the present improvements, it will be noted that the same generally includes in its organization a suitable frame or stand 1 provided at one end thereof with a feeding table 2 for the unslitted blank. This feeding table leads to a suitable form of cutting mechanism designated by the letter C and principally comprising the cutting and slitting rollers 3 and 4 which produce a slitted blank having the grooved or channeled formation referred to.

After the blank has been operated upon by the slitting and cutting rollers 3 and 4 it passes through the strippers 5 and also through the guideway 6 of the feeding table 7, to the novel feeding and guiding unit G. The unit G is of special construction to adapt the machine to the grooved type of fabric. To that end the feed rollers 8 and 9 are provided with parallel annular ribs 10 respectively which interfit with the grooves *a* in the slitted blank to thereby positively engage and guide the same as it is delivered to the expanding means. It will therefore be apparent that after the slitted blank is cut or slitted by the rollers 3 and 4 to produce the formation shown in Figures 9 and 10, its rib and groove characteristic is preserved and utilized by the primary ribbed feeding and guiding rollers 8 and 9 to thus positively grip and hold the sheet against slipping until the extreme end of the slitted blank has been properly gripped by the feeding instrumentalities of the divergent jaws J and J' constituting the expanding means.

The feeding and guiding jaws J and J'

are of identical construction and embody the same structural features for gripping and guiding the slitted blank. And, for the purpose of adjusting the said jaws in proper divergent relation with reference to each other, the inner ends thereof are pivotally supported as at 11 on the standards 12 which carry the primary feeding and guiding rollers 8 and 9, while the outer ends thereof are adjustably attached as at *x*, to the slotted standards 13 and 14 carried by the main frame 1. As will be observed from Figure 2, the jaws J and J' are provided with the expanding edges E and E' arranged divergently laterally, or in the plane of feed 80 of the slitted sheet, while the said upper and lower jaws J and J' also diverge vertically from the plane of the slitted sheet to produce the fan-like expansion thereof as the sheet is pushed through the jaws. 85

A particular feature of the present invention is, that each of the expander jaws is equipped with a progressively arranged series of ribbed feeding and guiding units cooperating with the primary ribbed feeding rollers 8 and 9 to properly feed, guide and hold the sheet throughout the expanding operation. In this expanding operation, as the slitted blank is delivered from the primary feeding and guiding rollers 8 and 9, 95 the central portion thereof will be gripped by the first set of the feeding and guiding units of the opposite expander jaws, and as each succeeding unit of the jaw picks up the slitted blank it will be expanded laterally 100 by reason of the diverging relation of the jaws with respect to the normal flat plane of the sheet, while the margins or edges of the sheet are tightly held or gripped by the interlocking engagement of the grooved 105 sheet with the ribbed feeding and guiding units as shown in Figure 4 for example.

Referring more specifically to the novel structural features and arrangement of the feeding and guiding units carried by the 110 divergently related jaws J and J' it will be observed from Figures 3, 4 and 5 that each of said units essentially comprises a pair of upper and lower feed rolls 20 and 21, each roll having upon its periphery a series of 115 parallel annular ribs 23 of a width fractionally less than the width of the grooves *a* in the slitted blank, so as to interlock with said grooves of the blank to compel a straight movement thereof and locking the sheet 120 against lateral displacement or sidewise slipping. At the same time the ribs 23 of the feeding rolls frictionally grip the blank with sufficient firmness to positively propel or push the same through the channel or pass 125 formed between the ribs 24 and 24^a projecting from the adjacent faces of the complementary die members 25 and 26. These die members 25 and 26, together with the feed rolls 20 and 21, constitute the feeding and 130

guiding unit for feeding, guiding and holding the grooved and slotted blank during its passage through the expander jaws J and J'.

- It will be seen from the drawings that 5 the guiding die members 25 and 26 of each expander jaw are arranged successively one in advance of the other but have a progressive inwardly off-set relation as clearly shown in Figures 2 and 5 of the drawings, 10 whereby the entire series of the die members or plates, for each jaw, will be arranged at the edge of the jaw along a line oblique to the line of blank feed. At the same time the guiding die members or plates of each 15 jaw are disposed in matching relation, that is with their ribs in parallel and continuing relation so that there will be continuous communication between the ribbed and grooved faces of the abutting die plates or 20 members in order that the grooved slotted blank may freely slide over and through the ribbed surfaces of the die members or plates as the blank is advanced or pushed by the action of the ribbed feed rolls. 25 Furthermore, it is preferable in constructing the die guiding plates or members 25 and 26 to form on their outer slanting or oblique faces, shoulders 26^a which are arranged in progressively stepped relation thus providing 30 a construction wherein the inner faces of the expander jaws are not only formed along an inclined or oblique line but are of a continuous stepped formation as clearly shown in the detail plan view of Figure 5 35 of the drawings. This stepped edge construction has heretofore been designated as E—E' for the respective jaws and facilitates the release of the blank over the edges of the jaws as it is expanded. 40 As shown very clearly in Figures 4 and 6 of the drawings the ribbed feeding rolls 20 and 21 are arranged immediately adjacent the guiding dies 25 and 26 at the inner sides of the latter so that the said rolls 45 and dies combine to form a ribbed and grooved pass through which the slotted blank is advanced by a pushing action on the feeding rolls. By reason of this relation of the feeding rolls to the guiding dies 50 along the side of the same, the said feeding rolls carried by each jaw are necessarily arranged in progressively divergent relation as may best be seen from illustration of Figure 5 of the drawings. 55 Any suitable driving means may be employed for imparting positive rotation to the feeding rolls carried by both the expander jaws. However for illustrative purposes there is shown the form of drive that 60 may be utilized. This drive includes suitably mounted spindles which carry the feeding rolls 20 and 21 and referring particularly to the arrangement of the parts of the drive shown in the drawings it will 65 be seen that the lower feeding roll 21 is

carried by a spindle 30 suitably journalled as at 31 in the jaw frame 32 and carrying at its outer end the driving gear 33 meshing with the driving gear 34 carried by the shaft or spindle 35 of the upper feed rolls 20 (see 70 Fig. 6). Thus, the upper and lower rolls of each feeding unit are driven by the intermeshing gears 33 and 34, and for the purpose of transmitting motion from the gears of one unit to the next the transfer 75 gears 36 may be used. Suitable adjusting screws S or their equivalent may be employed for shifting the journals of one roll with reference to the other to regulate or adjust the pass between the ribbed portion 80 of the feed rolls; and, as also shown in Figure 6, the die members 25 and 26 may be detachably fitted to the proper parts of the jaw frame 32 by fastenings 37 or the like.

For the purpose of actuating the gears 85 33 and 34 on the shafts of the ribbed feeding and guiding rolls, a driving gear 38 may be provided for each of the jaws, the same meshing with the gear 34 of the first feeding and guiding unit of the lower jaw J' (Fig. 90 1) and with the gear 33 of the first feeding and guiding unit of the upper jaw J. The said driving gear 38 may be driven by the gear 39 carried upon the shaft 40 which receives its power through the gear 41 meshing with the relatively large driving gear 42 which in turn receives its power from the main drive gear 43 carried by shaft 44 journalled in the main frame. The said relatively large gear 42 also serves to drive 100 the gears 3^a and 4^a upon the cutting and slitting rollers 3 and 4 as will be seen from Figure 1 and, also through the gear 41 on shaft 40, drives the primary ribbed feeding and guiding rollers 8 and 9 of the unit G. 105

From the foregoing it will be apparent that the novel and distinguishing characteristic of the present invention is the provision of the feeding and guiding devices so designed and arranged as to function with 110 a grooved formation of slotted blank, so that as such blank is opened out into meshes by reason of the divergent relation of the expander jaws the opposite edges of the blank will remain firmly interlocked with 115 not only the feeding rolls but with the guiding dies until the last strands of the sheet are opened into meshes. It is on account of this particular combination of elements, together with the grooved character 120 of the sheet that the latter is tightly held against slipping or displacement at any stage of the expanding operation. It is therefore possible, in an expanding machine provided with the improvements herein described to operate the machine at great speed while at the same being assured of a uniform and properly expanded product. 125

I claim:—

1. A metal expanding machine including 130

- 4 a pair of divergent expander jaws, guides at the edges of the jaws having an interlocking engagement with the edge portion of the sheet, and feeding means for advancing the sheet over the guides. 5
2. A metal expanding machine including a pair of divergent expander jaws, ribbed guides at the edges of the jaws, and ribbed feeding devices cooperating with said guides. 10
3. A metal expanding machine including an expander member having a ribbed and grooved guiding pass extending lengthwise thereof, and feeding means for advancing a slotted grooved sheet through said pass. 15
4. A metal expanding machine including an expander member provided at one edge thereof with a ribbed and grooved guiding pass adapted to interlock with a slotted grooved sheet, and ribbed feeding elements arranged at one side of the pass and having an interlocking and feeding engagement with the sheet. 20
5. A metal expanding machine including an expander member provided at one edge 25 with superimposed ribbed guiding dies forming between them a ribbed and grooved guiding pass, and superimposed pairs of ribbed feeding rolls arranged at one side of the said pass and having an interlocking and feeding engagement with the sheet. 30
6. A metal expanding machine including a pair of divergent expander jaws each of which jaws is provided along one edge with ribbed guiding dies having an interlocking engagement with a grooved slotted sheet, and progressively arranged pairs of ribbed feeding rolls carried by each jaw at one side of the dies and having an interlocking and feeding engagement with the sheet. 35
7. A metal expanding machine including a pair of divergent expander jaws carrying ribbed feeding and guiding elements having interlocking engagement with a grooved slotted blank, and a primary set of ribbed feeding rollers arranged adjacent the convergently disposed ends of the jaws. 45
8. A metal expanding machine including a pair of divergent expander jaws each having a series of progressively stepped guiding dies having an interlocking engagement with a grooved slotted sheet, and a ribbed feeding device arranged adjacent each die and having an interlocking and feeding engagement with the sheet. 50
9. A metal expanding machine including a pair of divergent expander jaws each carrying a series of feeding and guiding units progressively arranged in stepped relation, each of said feeding and guiding units including a pair of feed rolls adapted to have an interlocking engagement with the slotted metal blank and a pair of dies having guid- 55
- ing ribs on their opposing faces to register and interlock with the slotted metal blank. 65
10. In a metal expanding machine including a pair of divergent expander jaws each carrying a series of feeding and guiding units arranged to progressively engage a slotted metal sheet in a line diagonal to the line of feed, each of said units comprising sheet feeding elements having an interlocking and feeding engagement with the sheet, and stationary die elements also having a registering and interlocking engagement with the sheet. 70
11. A metal expanding machine including a pair of divergent expander jaws each carrying a series of feeding and guiding units arranged in inwardly off-set relation the off-setting being in a line oblique to the line of feed, and said units including ribbed feeding elements having a feeding and interlocking engagement with the metal sheet, and ribbed stationary guides having an interlocking engagement with the metal sheet. 75
12. A metal expanding machine including a pair of divergent expander jaws each carrying feeding and guiding means for a grooved slotted sheet, said feeding and guiding means including upper and lower ribbed feed rolls providing therebetween a channeled feed pass, and upper and lower stationary ribbed dies also providing therebetween a channeled guiding pass. 80
13. A metal expanding machine including a pair of divergent expander jaws adapted to receive a previously slotted blank, stationary blank guiding and holding means at the edges of the jaws, and separate feeding means for advancing the blank over the guiding and holding means. 85
14. A metal expanding machine including a pair of divergent expander jaws adapted to receive a previously slotted blank, stationary blank guiding and holding means at the edges of the jaws, and separate ribbed feeding devices cooperating with said guiding and holding means. 90
15. A metal expanding machine including a pair of expander jaws, ribbed guides for the blank carried by the jaws, and feeding means for advancing the blank over the guides. 100
16. A metal expanding machine including a pair of divergent expander jaws adapted to receive a previously slotted grooved blank, guiding means carried by the jaws for said blank and non-cutting feeding elements for advancing the blank over the guides. 105
